METHOD OF MAKING MOLDS HAVING
TRANSITION CORES

Raymond J. Miller, Detroit, Mich., assignor, by direct and means assignments, to Miller Engineering Corporation, Detroit, Mich., a corporation of Michigan

Application September 21, 1942, Serial No. 459,106

12 Claims. (Cl. 22—131)

This invention relates to the art of casting, and more particularly to the formation of molds having deep partings extending into both the cope and drag sections of a flask and disposed in transition mold shaping members formed by a reproductive process and extending throughout the usable portions of the mold-forming substance in both the cope and drag sections of the flask.

In certain types of casting equipment such as the so-called Capaco process as disclosed in Patent No. 2,201,037, issued May 14, 1940, molds of predetermined external size and shape are formed by applying a mold-forming substance to a pattern positioned in a flask. The mold-forming substance used in such casting operations is preferably a porous or granular material or a substance like plaster susceptible of becoming porous after formation.

In these methods of casting, production patterns are secured to a flask, and the combined pattern and flask constitutes a die pattern. The external dimensions of the die patterns may be varied through relatively wide limits. However, it is desirable that the mold-forming equipment be standardized as much as possible, since different flasks are required in the formation of molds of different sizes, and specialized drying equipment conforming generally to the external contour of the mold-forming sections is necessary in the operation of the process.

To permit greater flexibility in the use of this equipment the die pattern may be divided into a plurality of sections of uniform size. A single pattern may extend over one or more of these sections, and patterns of differently shaped articles may be positioned adjacent each other in the flask.

Plaster molds having mold impressions of a plurality of different articles to be reproduced may thus be formed in the cope and drag sections of a mold. In order that the matched pattern impressions of the cope and drag sections of the mold may accurately align with each other with a sufficient degree of accuracy to provide good castings, the pattern segments must be accurately machined to predetermined horizontal and vertical dimensions.

In the use of present methods a parting has a vertical limit of from the base of the pattern to the top of the cope or drag respectively, and the parting cannot extend through the base of the pattern.

By these methods it is also necessary that the vertical dimensions of the casting to be formed

lie within the usable portions of the plaster of the cope and drag sections, since it is impossible to cast articles having a vertical dimension greater than the distance from the outside limit of the bottom of the drag to the top of the cope. This dimension constitutes a limiting factor in the use of these casting methods because of the type of mold-forming equipment used.

In a typical die pattern a pattern base of $\frac{1}{8}$ " is used as standard, and the vertical height of the plaster mold of the cope or drag sections is approximately $2\frac{1}{8}$ ". In this equipment it is impossible to extend a parting into more than approximately $\frac{1}{8}$ " of the $\frac{1}{8}$ " of the base, and it is necessary that approximately $\frac{1}{4}$ " of plaster lie above the top-most portion of the pattern of the article being formed. It is thus impossible with this equipment to form a casting having a parting line extending more than approximately $3\frac{1}{4}$ " vertically, $\frac{1}{8}$ " of which may extend into the base.

This invention is directed to the development of an improved method whereby the vertical height of a parting may extend from the bottom limit of the drag to the top limit of the cope in a system where disassociated patterns are employed. This may be accomplished by the use of transition mold shaping members extending into both the cope and drag sections of the mold.

These transition mold shaping members may be formed by a reproductive process directly from the pattern of the article to be formed. The reverse side of the transition mold shaping members are contoured to eliminate back-draft, and patterns having a contour to receive the reverse side of the transition mold shaping members are formed by a reproductive process directly from mold shaping members. It is thus possible to form castings wherein the parting may extend vertically throughout the entire usable mold-forming substance in both the cope and drag.

An object of this invention resides in the development of an improved method whereby the parting line may extend to the full limits of the usable portions of the mold-forming substance in both the cope and drag of molds formed by die patterns.

A further object resides in the provision of an improved casting process whereby relatively deep articles may be cast in transition mold shaping members formed by a reproductive process.

Another object is to provide an improved method of making accurately matched core boxes and patterns by a reproductive method thereby

eliminating the ordinary laborious processes of conforming core boxes and patterns.

Still a further object of the invention resides in the provision of a novel method of making core boxes by a reproductive process to accurately embody the exact contour of the desired core in such a manner that no finishing operations are required on the core-forming surfaces of the core box.

Another object is to provide an improved method of producing accurately aligned core and pattern members directly from a master pattern.

Other objects and advantages of this invention will be apparent from the following detailed description considered in connection with the accompanying drawings, submitted for purposes of illustration only, and not intended to define the scope of the invention, reference being had for that purpose to the subjoined claims.

In the drawings wherein similar reference characters refer to similar parts throughout the several views:

Fig. 1 is a perspective view of a master pattern of an article requiring a parting line of greater vertical height than the combined height of a pattern base and the usable portion of one mold.

Fig. 2 is a sectional view illustrating the first step in the practice of the invention wherein the article of Fig. 1 is embedded in any suitable parting material.

Fig. 3 is a sectional view showing one step in the formation of a transition core-forming member by a reproductive process made directly from a master pattern of the article to be cast.

Fig. 4 is a sectional view, illustrating the shaping of the reverse side of the core box-forming member to a desired configuration.

Fig. 5 is a sectional view illustrating the formation of a female member from which the cope production pattern is formed, the female member being formed by a casting operation from the reverse side of the transition mold shaping member.

Fig. 6 is a sectional view illustrating the formation of a companion transition mold shaping member.

Fig. 7 is a sectional view illustrating the shaping of the reverse side of the companion transition mold shaping member to embody a desired shape.

Fig. 8 is a sectional view illustrating the formation of a female member from which the drag production pattern is formed, the female member being formed by a casting operation from the reverse side of the companion transition mold shaping member.

Fig. 9 is a sectional view illustrating the formation of a male production pattern from the drag female member.

Fig. 10 is a sectional view illustrating the formation of a male production pattern from the female cope member.

Fig. 11 is a sectional view illustrating the formation of the upper half of the drag core box by a reproductive method.

Fig. 12 is a sectional view illustrating the formation of the upper half of the cope core box by a reproductive method.

Figs. 13 and 14 are sectional assembly views of the drag and cope core boxes respectively.

Fig. 15 is a sectional view of the male cope production pattern being used as a part of a die pattern to form a plaster mold.

Fig. 16 is a view similar to Fig. 15 illustrating the use of the drag production pattern to form a

plaster mold conforming to the external contour of the drag core.

Fig. 17 is a partially assembled view showing the transition mold shaping members in place.

5 Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

10 15 Referring now to the drawings, Fig. 1 is illustrative of a pattern of any article 20 which may be formed by a casting operation. The article 20, for example, may be an angle member having a substantially flat smooth plate 22 intersected by another substantially flat smooth plate 24 at right angles thereto in such a manner as to provide an area 26 of back draft to a vertical movement of the cope section of a mold relative to the drag section thereof.

20 25 If the vertical height of a required parting, such, for example, as the distance from the apex 28 to the base 30 of the article 20, and the length of both of the plates 22 and 24 are greater than the usable portion of plaster of either the cope 30 or drag sections of a plaster mold plus the vertical height of one pattern base it would be impossible to use the plaster molding process by methods heretofore known in this art.

30 35 To cast the article 20 in a plaster mold it is necessary that the parting between the upper and lower mold sections extend into both the cope and drag sections. Although this has heretofore been impossible it may now be accomplished by the use of transition cores extending into both the 40 cope and drag of the mold. The complications heretofore encountered in making transition cores to accurately match both the pattern of the article to be formed and the production pattern to provide the core impressions, has rendered their 45 use impractical, if not impossible. However, by this method of forming molds, these complications may be readily overcome by the formation of matched core boxes and production patterns by a reproduction method directly from a model of the article to be reproduced.

50 55 The article 20 may be positioned on any suitable parting substance 32 such for example as molding clay, dental plaster, etc. The pattern 20 may be embedded in the substance 32 to approximately midway as illustrated by the line 34 so that a portion of the pattern 20 is above the line 34 and the remainder is below the line 34. The parting substance 32 is shaped with reference to the surfaces 22 and 24 of the article 20 in such a manner as to eliminate back draft, as by the formation of angularly related surfaces 36 and 38. The angle of the surface 38 is such as to relieve the back draft at the portion 26 of the pattern.

60 65 Referring now to Fig. 3 it will be observed that a frame 40 is superimposed on the parting substance 32 and any suitable moldable substance 42 such for example as plaster or an alloy consisting of approximately 42% tin and 58% bismuth is applied to the exposed surface of the pattern 20 and the parting substance 32 to form in the frame 40 a transition cope mold shaping member having a surface accurately conforming to the contour of the exposed portion of the pattern 20 and the parting substance 32.

70 75 As illustrated in Fig. 4 the substance 42 may be

cut away to provide a transition cope mold shaping member 44 with angularly related surfaces 46 and 48 generally conforming to the contour of the members 22 and 24 of the pattern 20 and filling the space within the parting substance 32 below the line 34.

Referring now to Fig. 5 it will be observed that a frame 50 is superimposed on the parting substance 32, and any suitable moldable substance 52 such for example as an alloy of the so-called "Cerro" type consisting for example of 42% tin and 58% bismuth is applied to the exposed surface of the transition cope mold shaping member 44 and parting substance 32 to form within the frame 50 a female member 54 conforming to the contour of the exposed portion of the transition cope mold shaping member 44.

The frame 50 is preferably formed to accurate external dimensions for use in an alignment frame consisting of a right angle to engage the side walls of superimposed frames in the subsequent formation of pattern equipment of the die pattern type.

After solidification of the substance 52 of which the female member 54 is formed, the frame 50 with the transition cope mold shaping member 44 and pattern 20 in place therein may be inverted as illustrated in Fig. 6. The initially applied parting substance 32 may now be removed and a frame 56 superimposed on the frame 50. Any suitable moldable substance 58 such for example as plaster or cerrobend may be applied to the exposed surfaces of the pattern 20, the transverse cope mold shaping member 44 and the female member 54 within the confines of the frame 56.

The frame 56 need not accurately conform with the shape and contour of the frame 50, since all that is necessary is that it confine the substance 58 to cover the portion of the pattern 20, formerly covered by the parting substance 32.

After the substance 58 has set, the frame 56 may be removed. The plaster or other substance 58 may then be partially cut away as illustrated in Fig. 7 to eliminate back draft and to form a transition drag mold shaping member 60 conforming to the contour of the portion of the pattern 20 formerly covered by the parting substance 32.

As illustrated in Fig. 8 another frame 62 of accurate external dimensions may be superimposed on the frame 50 having the female member 54 therein. The frame 62 may be accurately aligned with the frame 50 by means of a right angle frame 64. Any suitable moldable substance 66 such for example as cerrobend or cerrobase may be introduced into the space within the frame 62 to cover the exposed surface of the drag transition mold shaping member 60 and the edges of the cope transition mold shaping member 44 to form in the frame 62 a female member 68 of the transition core and pattern members.

The frame 62 with the female member 68 therein may be removed, and as illustrated in Fig. 9, may be placed in the right angle frame 64. A male pattern frame 70 having accurately finished external surfaces, may be superimposed on the frame 62 and aligned therewith by means of the right angle frame 64. A riser frame 72 may be superimposed on the male pattern frame 70 and aligned therewith as illustrated. The use of the riser frame is more clearly disclosed in my copending application Serial No. 454,831, filed August 14, 1942.

Any suitable mold-forming substance 74 such for example as cerrobase may be introduced into

the space within the female member 68 and frames 70 and 72 to form therein a male production pattern 76 of the female member 68 of the transition drag mold shaping member 60. The frame 70 may be formed with an inwardly-extended bead 78 to engage and securely hold the substance 74 of which the male production pattern 76 is formed.

Referring now to Fig. 10 it will be observed that the frame 50 housing the female member 54 having the external contour of the cope transition mold shaping member 44, may be inverted and positioned in the right angle frame 64. A male production pattern frame 80 having accurately formed external surfaces may be superimposed on the frame 50 and aligned therewith by the right angle frame 64. A riser frame 82 corresponding to the riser frame 72 illustrated in Fig. 9 may be superimposed on the male production pattern frame 80. The space within the female member 54 and frames 80 and 82 may be filled with any suitable moldable pattern-forming substance 84 such for example as cerrobase to form a male production pattern 86 of the external surface of the cope transition core-forming member 44.

Fig. 11 illustrates the formation of the top half of the drag mold shaping core box. A frame 88 may be superimposed on the frame 62 housing the female member 68 from which the drag pattern 66 was formed. The drag transition mold shaping member 60 is positioned in the female member 68, then the members 54, 44, and the pattern 20 are removed. Any suitable moldable substance 90 such for example as cerrobase may be introduced into the space within the frame 88 to form the upper half 92 of the drag mold shaping core box.

After solidification of the substance 90 of which the upper half 92 of the drag mold shaping core box is formed, the frame 88 having the upper mold shaping core box member 92 therein is removed from the frame 62 and the female member 68. The drag transition mold shaping member 60 may then be removed and the elements 66 and 92 reassembled as illustrated in Fig. 13 having a mold cavity 94 accurately conforming to the contour of the transition drag mold shaping member 60 for producing the drag transition mold shaping member. A suitable opening 96 may be provided to permit the introduction of a mold-forming substance, such, for example, as plaster or a gypsum compound to form the desired drag transition mold shaping member 98 (Fig. 17) extending from the drag portion 120 of the mold into the cope portion 128.

To form the upper half of the cope mold shaping core box a frame 104 may be superimposed on the frame 50 housing the female member 54 having the imprint of the contoured surface of the cope transition mold shaping member 44. The transition mold shaping member 44 is left in place in the female member 54 and the pattern 20 is removed. Grooves 106 may be formed in the surface of the moldable substance 52 outside of the female impression 54 of the transition mold shaping member 44.

A moldable substance 108 such for example as cerrobase is then introduced into the space within the frame 104 to fill the space surrounding the transition cope mold shaping member 44 and the portion of the female member 54 above the line 34. Ridges 110 projecting into the grooves 106 are formed to accurately locate the upper half 112 of the cope mold shaping core box

with reference to the lower half constituting the female member 54.

To form the cope mold shaping member the frame 104 housing the upper half 112 of the cope mold shaping core box may be removed from the frame 50 and the transition mold shaping member 44 removed from the female member 54. The upper half 112 of the cope core box may then be reassembled on the female member 54 as illustrated in Fig. 14 to form a cope mold shaping core mold 114 accurately conforming to the external contour of the transition cope mold shaping member 44.

Plaster or other suitable mold-forming substance may then be introduced into the mold shaping core box through a suitable aperture 116 to form a cope transition mold shaping member 118 (Fig. 17).

After the drag and cope mold shaping core box-forming members of Figs. 13 and 14 have been formed they may be assembled as illustrated therein, and any suitable mold-forming substance such for example as plaster may be introduced to form the transition mold shaping members. After the mold shaping members have attained a substantially predetermined set in the core boxes they may be removed therefrom and subjected to a drying operation to drive off virtually all moisture whereupon cores of relatively porous structure having fine-grained, hard surfaces are provided to form the mold cavity 120 of the article 20 as illustrated in Fig. 17.

As illustrated in Figs. 15 and 16 the cope and drag production pattern members 86 and 76 respectively are mounted on flasks 122 and 124. The patterns 86 and 76 being carried by their respective frames 80 and 70 are formed to accurate horizontal and vertical dimensions for reception in the flasks 122 and 124.

After assembly as illustrated in Figs. 15 and 16, mold-forming substance such for example as plaster 126 may be applied to the die patterns composed of the combined flask and pattern members to provide cope and drag plaster molds 128 and 130 respectively having female impressions formed therein conforming to the shape of the contoured surfaces of the cope and drag mold shaping members 118 and 98 respectively.

As illustrated in Fig. 17 the transition drag mold shaping member 98 is assembled in the drag mold 130, and the transition cope mold shaping member 118 is superimposed on the drag core 98. The cope mold 128 may be placed on the transition cope mold shaping member 118 and drag mold 130 to complete the mold assembly. Suitable riser and feeder chambers may be provided to supply molten alloy or metal to the cavity 120 formed between the mold shaping members 118 and 98 respectively.

As the alloy or metal is poured into the mold entrained air and gases formed during the pouring and cooling operations diffuse through the walls of the cores and molds respectively to provide a solid homogeneous casting having a smooth-surface texture accurately conforming to the shape and contour of the desired article.

The mold-forming substances employed in the various steps illustrated herein may vary through wide limits. For example, the moldable substance 32 applied in the step illustrated in Fig. 2 to form a parting may be virtually any moldable substance capable of assuming and maintaining a desired shape. The substance applied in the step illustrated in Fig. 3 to form the transition mold shaping member may be virtually any sub-

stance, preferably possessing the characteristics of substantially constant volume upon solidification. It is also desirable that this substance be readily workable so that the desired contour of the transition mold shaping member may be readily applied thereto.

It will be apparent that if the substance employed in the various steps recited above do not possess the characteristic of constant volume upon change of state from liquid to solid suitable allowance should be made for contraction or expansion of the substance so that the resulting mold-forming members will accurately embody the desired contour.

15 I claim:

1. The method of making cooperating mold and mold shaping members to define a casting cavity comprising contouring the side of a mold shaping member opposite from the casting cavity to permit removal of the mold section in the direction of back draft, applying a moldable substance to the contoured side of the mold shaping member to provide a female impression thereof, and applying a moldable substance to the female impression to form a production die pattern thereof.

2. The method of making matched core boxes for forming mold shaping members comprising successively applying moldable substances to spaced portions of a pattern to form mold shaping members, contouring the reverse sides of the mold shaping members to permit removal of the mold shaping members in the direction of back draft, applying moldable substances to the contoured sides of the mold shaping members to produce mold shaping core-boxes, and applying moldable substances to the pattern side of the mold shaping members to provide mold shaping core boxes for the pattern-forming sides of the mold shaping members.

3. The method of forming core boxes for forming mold shaping members comprising applying parting material to a pattern to allow removal of a mold section in the direction of back draft, applying a moldable substance to the exposed portion of the pattern and parting material, contouring the reverse side of the applied substance to provide a mold shaping member contoured to allow removal of said member in the direction of back draft, and forming an impression of the contoured side of the mold shaping member.

4. The method of making a box for forming mold shaping members comprising applying a moldable substance to a portion of a pattern to provide a mold shaping forming member, contouring the reverse side of the mold shaping forming member, applying a moldable substance to the contoured side of the mold shaping forming member to provide a mold shaping box portion for the contoured side, and applying a moldable substance to the mold shaping forming member to provide a mold shaping box portion for the pattern-forming side of the pattern side of the mold shaping forming member.

5. The method of making matched mold shaping and pattern members comprising applying a moldable substance to a pattern to form a parting thereon, applying a moldable substance to the exposed surface of the pattern to provide a transition mold shaping forming member, contouring the reverse side of the transition mold shaping forming member, applying a moldable substance to the contoured side of the mold shaping forming member to provide a member having a female

impression thereof, and forming a production die pattern from the member having said female impression to embody the contour of the contoured side of the mold shaping forming member.

6. The method of making a core box for forming a mold shaping member comprising applying parting material to a pattern to form a parting, applying a moldable substance to the exposed surface of the pattern to provide a mold shaping forming member, contouring the reverse side of the mold shaping forming member, applying a moldable substance to the contoured side of the mold shaping forming member to provide a female receptacle, inverting the assembly, removing the pattern, and applying a moldable substance possessing the characteristic of solidifying to the mold shaping forming member and female receptacle to form a mold shaping core box.

7. The method of making a matched mold shaping and pattern assembly comprising applying parting material to a pattern to form a parting thereon, applying a moldable substance to the exposed surface of the pattern to provide a mold shaping forming member, contouring the side of the mold shaping forming member remote from the pattern contacting side, applying a moldable substance to the contoured side of the mold shaping forming member to provide a female member, applying a moldable substance to the female member to form a production pattern, assembling the mold shaping forming member and female member, and applying a moldable substance to the mold shaping forming member and female member to form a mold shaping box.

8. The method of making mold shaping boxes comprising applying parting material to one of the contoured sides of a unitary pattern to form a parting thereon, applying a moldable substance to the exposed surface of the pattern and parting material to provide a transition mold shaping forming member, contouring the reverse side of the transition mold shaping forming member, applying a moldable substance to the contoured side of the mold shaping forming member and parting material to provide a female impression thereof, inverting the female impression and transition mold shaping forming member, removing the initially applied parting material from the pattern and transition mold shaping forming member, applying a moldable substance to the exposed surface of the pattern and transition mold shaping forming member to provide a companion mold shaping forming member, contouring the reverse side of the companion transition mold shaping forming member, applying a moldable substance to the contoured side of the companion mold shaping forming member to provide a female impression thereof, separating the female impressions and their associated mold shaping forming members from the pattern, assembling the transition mold shaping forming members and their associated female impressions and forming mold shaping box members by applying a moldable substance to the exposed surface of the transition mold shaping forming members and female receptacles.

9. The method of making matched mold shaping member boxes and patterns comprising applying parting material to one of the contoured sides of a pattern to provide a parting thereon, applying a moldable substance to the exposed surface of the pattern to provide a mold shaping forming member, contouring the reverse side of the mold shaping forming member, applying a moldable substance to the contoured side of the

5 mold shaping forming member to provide a female impression thereof, inverting the female impression and mold shaping forming member with the pattern and initially applied parting material in place, removing the parting material, applying a moldable substance to the exposed surface of the pattern and mold shaping forming member to provide a companion mold shaping forming member, contouring the reverse side of the companion mold shaping forming member, applying a moldable substance to the contoured side of the companion mold shaping forming member to provide a female impression thereof, separating the female impressions and their associated mold shaping forming members from the pattern, applying a moldable substance to the female impressions to form production patterns, assembling the mold shaping forming members and their associated female impressions, and forming mold shaping member boxes by applying a moldable substance to the exposed surface of the mold shaping forming members and female impressions.

10. The method of forming molds having casting cavities embodying back draft and having partings extending from the cope section into the drag section comprising embedding a unitary master pattern in parting material, contouring the parting material to allow removal of a mold shaping member from the master pattern in the direction of back draft, applying a moldable substance to the master pattern and parting material to provide a mold shaping member separable from the master pattern in the direction of back draft, contouring the exposed surface of the mold shaping member to allow removal of a mold member therefrom in a plane perpendicular to the juncture between the cope and drag sections of the mold, applying a moldable substance to the contoured surface of the mold shaping member and parting material to form an impression thereof, forming a productive pattern member by casting a moldable substance into said impression, forming core-box members for making mold shaping members by applying moldable substances to opposite sides of the contoured mold shaping member, and using said production pattern and core-box members in the formation of molds.

11. The method of casting articles having a vertical height greater than the usable mold investment of a single cope or drag flask plus the usable depth of a single pattern carrying base and including back draft comprising embedding a master pattern of said article in parting material to establish a parting line intermediate cope and drag flasks, contouring the parting material to permit removal of a mold shaping member from the master pattern in the direction of the back draft, applying a moldable substance to the exposed portion of the master pattern and parting material to provide a mold shaping member surrounding the portion of the master pattern embodying back draft, contouring the exposed surface of the mold shaping member, forming a production pattern embodying the contoured surface of the mold shaping member, forming a production core-box embodying the contours of the mold shaping member, and using said production pattern and core-box members in the formations of 70 molds for the casting of said articles.

12. The method of casting articles having a vertical height greater than the usable mold investment of a single cope or drag flask plus the usable depth of a single pattern carrying base comprising embedding a master pattern of said

article in parting material to establish a parting line intermediate cope and drag flask, applying a moldable substance to the exposed portion of the master pattern and parting material to provide a cope mold shaping member, contouring the exposed surface of the mold shaping member, applying a moldable substance to the contoured surface of the mold shaping member and parting material to form a cope impression thereof, removing the parting material, applying a moldable substance to the portion of the master pattern initially contacting the parting material to provide a drag mold shaping member, contouring the exposed surface of the drag mold shaping mem-

ber, applying a moldable substance to the contoured surface of the drag mold shaping member and the exposed surfaces of the master pattern and cope mold shaping and impression member to provide a drag impression, forming production cope and drag patterns by casting a moldable substance into said cope and drag impressions, forming cope and drag production core-boxes embodying the contour of opposite sides of the cope and drag mold shaping members, and using said production pattern and core-box members to form molds for casting said articles.

RAYMOND J. MILLER.
